UNITED STATES PATENT OFFICE.

FRED A. FOCKS, OF CRANE, MISSOURI.

COLLAPSIBLE CRATE.

1,156,221.

Specification of Letters Patent. Patented Oct. 12, 1915.

Application filed June 6, 1914. Serial No. 843,471.

To all whom it may concern:

Be it known that I, FRED A. FOCKS, a citizen of the United States, residing at Crane, in the county of Stone and State of Missouri, have invented new and useful Improvements in Collapsible Crates, of which the following is a specification.

This invention relates to collapsible crates and the principal object of the invention is 10 to provide a simple and efficient shipping crate which may be folded into compact form for return shipment or storage and which may be rapidly set up into operative position without the aid of tools.

15 Another object of the invention is the provision of simple and efficient guiding means which cheapen the construction and which effectively reinforce the crate.

Further objects of the invention will appear as the following description is read in 20 connection with the accompanying drawing, which forms a part of this application, and in which:—

Figure 1 is a side elevation. Fig. 2 is an 25 end elevation. Fig. 3 is a similar view showing the parts in partially folded form. Fig. 4 is a top plan view. Fig. 5 is a detail transverse sectional view on the line 5—5 of Fig. 4.

30 Referring more particularly to the drawing, 1 represents a bottom member which may be constructed of any suitable material of separate slats or a solid piece and which has secured to the sides thereof the reinforcing strips 2 to which are hinged the side members 3.

At the upper ends of each side member there is secured a clip 4 in which is mounted an eye member 5 engaged with the combined 40 reinforcing and guiding loops 6 carried by the member 7. This top member is constructed of end pieces 8 and side members 9 and a covering either of slats or a solid piece as may be found most desirable. The end 45 members 8 are provided with apertures 10 adjacent their center through which pass the combined guiding and reinforcing members 6. These members each consist as shown of a single strand of wire passed through the 50 aperture 10 and are bent back upon themselves having their terminals connected by twisting or otherwise, at the side edge of the

top member. In this instance the crate is shown as having its top member covered with slats 11 which serve as a means for 55 holding the reinforcing and guiding members against displacement. The same result would be obtained if a solid covering were employed.

Hingedly connected to the bottom member 60 1 are the end members 12 adapted to fold upon the bottom when in inoperative position and to lie between the side members when in operative position, being held against displacement by means of suitable fastening 65 devices here shown in the form of a staple 14 carried by the end member and a hook hasp 15 carried by the top member.

When the end members are folded upon the bottom member the side members may be 70 collapsed or folded upon the end members and in the inward movement of the side members it will be clearly noticed that the top member will also be drawn downwardly toward the bottom member where it may be 75 held upon the top of the side members with all parts in collapsed position by engaging the hook hasps on opposite ends of the top member with eyes 16 on the ends of the bottom member.

80 What is claimed is:—

In a folding shipping crate, a bottom member, a top member, guiding members comprising looped strands of wire extended centrally through the top member and having their terminals connected at the sides of the top member, end members hinged to the bottom member and adapted to fold thereon, side members hinged to the bottom member and having slidable connection with 85 one strand of each of the combined guiding and reinforcing members, said side members adapted to fold upon the end members and the top to fold upon the side members, and means for connecting the top to the end 90 members when the crate is in a set up position or to the bottom member when the crate is collapsed.

95 In testimony whereof I affix my signature in presence of two witnesses.

FRED A. FOCKS.
